DENTAL CARVING MACHINE

Harry Spiro, Chicago, Ill., assignor to Dental Research Corporation, Chicago, Ill., a corporation of Illinois

Application September 25, 1933, Serial No. 690,908

4 Claims. (Cl. 32—67)

This invention relates to improvements in dental carving machines and, more especially, to such a machine adapted for carving casts, adapters, artificial teeth, and the like, outside of the mouth. For example, in the making of bridges, artificial teeth, supports, and the like, it is frequently necessary or desirable to carve or chisel certain parts. One of the features of my invention is the provision of such a machine by which parallel surfaces may be readily made.

My invention is particularly applicable in connection with the making of bridges as disclosed in my co-pending application, Serial No. 632,203, filed September 8, 1932. In that application I disclosed a method of mounting bridges by the use of adapters on the abutment teeth. In the practice of that process it is necessary or desirable to provide said adapters with parallel surfaces. This can be accomplished very readily by the use of the carving machine herein disclosed.

Another feature of my invention is the provision of means for fastening a cast on a universally mounted support where the same is accessible by the carving tools.

Another feature of my invention is the provision of an improved dowel adapted to be imbedded in a cast to permit the same to be removably supported on the work support.

Other features and advantages of my invention will appear more fully as I proceed with my specification.

In that form of device embodying the features of my invention shown in the accompanying drawings—

Figure 1 is a view in side elevation; Fig. 2 is a view in front elevation; Fig. 3 is a view similar to Fig. 1; Fig. 4 is a vertical sectional view through one of the tool carriers; Fig. 5 is a similar view through the other tool carrier; Fig. 6 is a view taken as indicated by the line 6 of Fig. 5; Fig. 7 is a top plan view of a plate for mounting the dowel pins in the cast; Fig. 8 is a view taken as indicated by the line 8 of Fig. 7; Fig. 9 is an end view of the plate of Fig. 7; Fig. 10 is a vertical sectional view through the work support; and Fig. 11 is a top plan view of the work support.

As shown in the drawings, the device includes a platform 10, a post 11 mounted on the platform and a horizontal arm 12 carried by the post.

13 indicates a universally mounted work support with a base 14 adapted to be slidably posi-

tioned on the platform 10. The work support is universally mounted on the base 14.

The post 11 carries a horizontally reciprocable carving tool 15 and the arm 12 carries a vertically reciprocable carving tool 16.

For the purpose of mounting a cast (for example, a cast 17 as shown in Fig. 8) on the work support 13, said cast is provided with two dowels 18, 18 spaced a predetermined distance apart.

This is accomplished by providing a temporary supporting plate 19 (Fig. 7) upon which the cast 17 is made. The dowel pins 18 are positioned in this plate and the cast formed on the same, as shown in Fig. 8. The lower ends of the pins are provided with annular grooves 18a adapted to be engaged by keyhole slots 20 in the slide 21 in the plate 19. The upper ends of the dowels 18 are provided with annular recesses 18b to form locks with the plaster cast 17. The dowels 18 are positioned in the plate 19 and locked with the slide 21 and the cast is then formed on the plate. The slide 21 is then moved to release the lower ends of the dowels, whereupon the cast can be removed with the dowels remaining therein.

The work support 13 (see Fig. 10) is provided with two holes 22, 22 also spaced the same distance apart as the holes carrying the dowels in the plate 19. This work support 13 is also provided with a slide 23 having keyhole slots 24 similar to the slide 21 with its keyhole slots.

Consequently, after the cast 17 has been formed with the dowels 18 in place, it can be positioned on the work support 13 by placing the dowels in the holes 22 and locked thereon by movement of the slide 23 to cause the keyhole slots 24 to engage the grooves 18a in the lower ends of the dowels. In this way the cast can be releasably locked or positioned on the work support 13.

The universal mounting of the work support 13 on the base 14 is accomplished in the following manner. The base 14 is provided with a bifurcated support 30 having a horizontal pivot pin 31 carrying a worm gear 32. A worm 33 is provided for rotating the gear 32. This worm

33 may have an operating handle 34 and a micrometer screw 35 may be provided to show the degree of rotation. The upper portion of the wheel 32 carries a bifurcated support 36 with a pivot pin 37. A gear 38 is mounted on the bifurcated member 36 and is engaged by the worm 39. The pivot pin also carries the lower ends of a bifurcated support 40 which carries the work support 13. The axes of the pivot pins 31 and 37 are both horizontal and at right angles

50

55

55

to each other. The worm 39 is adapted to be operated by the handle 46 and a micrometer screw 47 may be provided to show the degree of rotation. By operating the handles 34 and 46, 5 either of the worms 33 and 39 may be turned in order to give any inclination desired to the work support 13.

The carving tool 15 is reciprocably carried in a sleeve 60. Reciprocation may be imparted to 10 the same by an operating handle 61 on the end of a spline shaft 62 extending through a worm 63. 64 indicates a gear engaging the worm 63. This gear is on a shaft 65 which also carries a gear 66 engaging the rack 67 on the post 11. 15 The shaft 65 is mounted on a carriage 65^a which is vertically movable on the post. By this construction, rotation of the handle 61 will rotate the worm 63 to raise or lower the tool 15. This, however, will not interfere with the reciprocation 20 of the tool. The spline in the shaft 62 engages a screw 68 on the worm 63 to impart rotation to the same, the spline permitting horizontal reciprocations of the shaft 62 through the worm. The inner end of the shaft 62 is provided 25 with an annular recess 70 engaged by a screw 71 on the end of the shaft 72 inside of the sleeve 60. The shaft 72 is preferably square to prevent rotation of the same in the sleeve. It will be seen, therefore, that the shaft 62 can be 30 used to reciprocate the shaft 72 in the sleeve 60 and that the annular recess 70 will permit rotation of the shaft 62 to rotate the worm 63 to raise or lower the tool, as desired.

The tool 16 is mounted for vertical reciprocation in the arm 12. This tool 16 is carried on the lower end of the shaft 80 which is provided with an adjustable stop 81 to limit the downward movement of the same. The lower end of the shaft 80 is also preferably provided with a 35 notch 82 adapted to be engaged by a spring-pressed ball 83 to yieldingly hold the tool in its uppermost position out of the way. In order to permit vertical adjustment of the stop 81, the same is made in the form of a sleeve threaded 40 on the inner sleeve 90 which is mounted on the shaft 80 by means of the set screw 91, a plurality of indentations 92 being provided for engagement by the inner end of the screw 91.

In the operation of the apparatus, the cast is made on a temporary supporting plate 19 and the dowels 18 correctly positioned therein. The cast may then be supported on the work support 13, the base of which rests on the platform 10. 5 The desired angle of the work support may then be obtained and by use of the tools 15 and 16, parallel surfaces as desired may be cut on the cast, or any part thereof.

While I have shown and described certain embodiments of my invention, it is to be understood that it is capable of many modifications. Changes, therefore, in the construction and arrangement may be made without departing from the spirit and scope of the invention as disclosed 15 in the appended claims, in which it is my intention to claim all novelty inherent in my invention as broadly as permissible, in view of the prior art.

What I regard as new, and desire to secure by 20 Letters Patent, is:

1. A dental carving machine, including; a platform; a post on the platform; a horizontally reciprocable carving tool mounted on the post, said tool being also vertically adjustable on the 25 post; a handle for horizontally reciprocating the tool; and means whereby rotation of said handle will vertically adjust the same on the post.

2. Apparatus as claimed in claim 1, in which the vertical adjustment of the tool is effected 30 through a rack bar carried by the post and engaged by a gear connected to the tool, said gear being rotated by rotation of said handle.

3. A dental carving machine, including; a platform; a post on the platform; a vertically 35 movable carriage on the post; a horizontally reciprocable carving tool mounted on the carriage; a handle for horizontally reciprocating the tool with respect to the carriage; and means whereby rotation of said handle will vertically adjust the 40 carriage.

4. Apparatus as claimed in claim 3, in which the vertical adjustment of the carriage is effected through a rack bar carried by the post and engaged by a gear mounted on the carriage, said 45 gear being rotated by rotation of said handle.

HARRY SPIRO.
